(57) CLAIM

The ornamental design for an exercise wall for sport purposes, as shown and described.

DESCRIPTION

FIG. 1 is a perspective top, front and left side view of an exercise wall for sport purposes showing my new design;

FIG. 2 is a perspective top, rear and right side view thereof;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a perspective top, front and left side view of a second embodiment of my new design;

FIG. 10 is a perspective top, rear and right side view thereof;

FIG. 11 is a front view thereof;

FIG. 12 is a rear view thereof;

FIG. 13 is a top view thereof;

FIG. 14 is a bottom view thereof;

FIG. 15 is a left side view thereof; and,

FIG. 16 is a right side view thereof.
